Joseph Klopfenstein

Castrov & Co.

UNITED STATES PATENT OFFICE.

JOSEPH KLOPFENSTEIN, OF ARCHBOLD, OHIO.

WIRE-STRETCHER.

SPECIFICATION forming part of Letters Patent No. 434,513, dated August 19, 1890.

Application filed May 23, 1890. Serial No. 352,937. (No model.)

To all whom it may concern:

Be it known that I, JOSEPH KLOPFENSTEIN, a citizen of the United States, residing at Archbold, in the county of Fulton and State of Ohio, have invented a new and useful Wire-Stretcher, of which the following is a specification.

The invention relates to improvements in wire-stretchers.

10 The object of the present invention is to provide a simple and inexpensive wire-stretcher adapted to be readily attached to a fence-post and capable of simultaneously stretching the wires of the fence to any desired tension and 15 of maintaining them at the same.

The invention consists in the construction and novel combination and arrangement of parts hereinafter fully described, illustrated in the accompanying drawings, and particularly pointed out in the claim.

20 In the drawings, Figure 1 is a perspective view of the wire-stretcher constructed in accordance with this invention. Fig. 2 is a vertical sectional view of the end post and 25 stretcher.

Referring to the accompanying drawings, 1 designates an end post of a fence provided near its top and bottom with eyes 2, in which is journaled a wire-stretcher 3, consisting of 30 a tube or pipe having attached to it wires 4. The tube or pipe 3, which is journaled in the eyes of the end post 1, is provided with a vertical series of perforations 4, adapted to receive the ends of the wires, whereby the latter are readily attached to the stretcher. The ends of the wires are passed through the vertical series of perforations 4 and brought 35 around one side of the tube or pipe and twisted upon the bodies of the wires, and 40 should the wires become broken they can readily be pieced and refastened. The upper end 6 of the tube is squared to adapt it to be readily engaged by a wrench or similar instrument to turn it and tighten the wires, and in order 45 to maintain the wires at any tension a pin 7 is employed, which passes through horizontal perforations 8 and engages the post, and the

said perforations 8 are arranged at various points along the circumference of the pipe or tube. A stop 9 projects from the lower portion of the end post and the tube or pipe rests upon the same, which prevents the wire just above the lower eye from coming in contact therewith and being broken. The intermediate posts 10 are arranged at suitable intervals and are provided with guides or staples 11 for the wires.

It will readily be seen that the herein-described improvement in wire-stretchers enables this class of fences to be cheaply, quickly, and conveniently erected, and that the wires can be drawn to any desired tension, thereby strengthening the fence and enabling the same to withstand the strain incident to its use.

From the foregoing description and the accompanying drawings the construction, operation, and advantages of the invention will be readily understood.

Having thus described my invention, I claim—

The combination of the end post provided with eyes 2, arranged near its top and bottom and having the stop or support 9, the tube or pipe journaled in the eye and resting upon the stop or support and provided with a vertical series of perforations to receive the wire, and having its upper end squared and adapted to be engaged by a wrench or similar tool and provided with perforations 8, arranged at various points on the circumference of the tube or pipe, and the pin 7, passing through one of the perforations 8 and engaging the end post and preventing the tube or pipe from turning in the eyes 2, substantially as described.

In testimony that I claim the foregoing as my own I have hereto affixed my signature in presence of two witnesses.

JOSEPH KLOPFENSTEIN.

Witnesses:

JOHN THEOBALD,
EMIL U. SCHNETZLER.
